(57) **CLAIM**

The ornamental design for a model vehicle clipless latch as shown and described.

DESCRIPTION

FIG. 1 is an upper, left, front perspective view of a model vehicle clipless latch showing our new design;

FIG. 2 is an upper, right, rear perspective view thereof;

FIG. 3 is a lower, right, front perspective view thereof;

FIG. 4 is a lower, left, rear perspective view thereof;

FIG. 5 is a front elevation view thereof;

FIG. 6 is a rear elevation view thereof;

FIG. 7 is an upper plan view thereof;

FIG. 8 is a lower plan view thereof;

FIG. 9 is a right-side elevation view thereof; and,

FIG. 10 is a left-side elevation view of a model vehicle clipless latch.

Only the left-side model vehicle clipless latch is shown. The right-side model vehicle clipless latch is a mirror image of the shown model vehicle clipless latch.
